OIL CRACKING SYSTEM

William T. Hancock, Long Beach, Calif.

Application October 9, 1934, Serial No. 747,552

6 Claims. (Cl. 196—110)

This invention has to do with improvements in liquid phase oil cracking systems, and has for its primary object to increase the yield and quality of gasoline obtainable by single passage 5 of the charging stock through a tube still.

In the more common oil cracking tube stills, the oil is pumped under high pressure through tubes within which the oil velocity is substantially constant throughout, except as it may 10 be increased by partial vaporization of the oil. Ordinarily the oil is heated to cracking temperatures and then immediately passed into a fractionating system, or sometimes by way of a conversion pressure chamber extraneous to the still. 15 I have found that by departing from the usual practice in tube still construction and operation in accordance with this invention, the yield of cracked distillate obtainable from the pressure distillate produced at the end of a single passage 20 of the charging stock through the still, can be increased in very substantial amounts, and the character of the product, particularly as regards its octane rating, greatly improved.

In carrying out the invention, I subject the 25 charging stock to cracking within the heating chamber of the still, and thereafter pass the oil through a "soaking" zone within that same chamber, in an extended path of flow and at a velocity substantially lower than the oil velocity in the cracking stage. Preferably the 30 cracking tubes will be located in the hottest portion of the heating chamber, since it is in these tubes that the oil will ordinarily be heated to its highest temperature, and the soaking tubes in 35 a somewhat cooler section, although the oil flowing through them will remain at or near the cracking temperature.

By increasing the oil passing capacity of the 40 soaking tubes as compared with the corresponding capacity of the cracking tubes, the velocity of flow through the former is substantially decreased; and by providing the soaking tubes in considerable number, the oil after leaving the cracking tubes is required to remain exposed to 45 the high temperatures in the heating chamber over an extended period of time, in order that conversion and reformation of the oil molecules may progress to the fullest possible extent before the oil leaves the still. Provision is also made 50 for maintaining the oil in the cracking and soaking tubes at any desired superatmospheric pressure, and if desired, for maintaining differential pressures in the two sets of tubes.

All these, as well as further objects and features of the invention will be more fully un-

derstood from the following detailed description of certain typical forms of the invention. Throughout the description, reference is made to the accompanying drawings, in which:

Fig. 1 is a sectional view showing a preferred 5 form of tube still;

Fig. 2 is an enlarged fragmentary view taken on broken line 2—2 of Fig. 1, showing the connection between the cracking and soaking tubes of the still; 10

Fig. 3 is an enlarged section taken on line 3—3 of Fig. 1 through the orifice valve;

Fig. 4 is a view similar to Fig. 1, showing a variational form of the invention;

Fig. 5 is a fragmentary enlarged view in the 15 aspect of line 5—5 of Fig. 4, showing the expansion fitting connecting the soaking and cracking tube sections; and

Fig. 6 is a view similar to Fig. 5 showing a variational placement of the orifice valve. 20

Referring first to Fig. 1, the still 10 comprises walls 11 enclosing a heating zone 12 which includes a radiant heating chamber 13, and a convection preheating chamber 14 separated from the first mentioned chamber by baffle wall 25 15. Hot combustion gases from burners 16 flow upwardly within chamber 13, then through space 17 above the baffle wall and downwardly through chamber 14 to the outlet flue 18. The temperatures are of course highest within chamber 13, 30 and the hereinafter described cracking and soaking tubes within that chamber are heated both by radiation and convection. Also, as will be readily apparent, the highest temperatures exist within the lower portion of chamber 13, and the 35 temperature of the combustion gases progressively decreases as the gases rise in passing toward the convection heating chamber 14.

The charging stock is fed to a bank 19 of oil 40 preheating tubes 20 within chamber 14, through line 21 and fitting 22 into the two lowermost horizontal tube rows 23 and 24, the oil in each of these lower rows of tubes flowing upwardly 45 through alternate rows, as indicated by the arrows, into the outlet line 25. Tube bank 19 serves 45 to preheat the oil to a suitable temperature prior to its passage into the cracking tubes, and if desired, to vaporize any predetermined range of the more volatile fractions of the charging stock prior to cracking. In cases where the tube 50 bank 19 is used to top as well as preheat the charging stock, line 25 is connected with a separator 26 of suitable design, from which the vapors pass through line 27 to be condensed, fractionated, or treated as may be desired. Any 55

suitable back pressure may be maintained within the preheating tubes by adjustment of valve 28 in the vapor line.

The unvaporized portion of the charging stock 5 leaves the base of separator 26 through line 29 and is forced under high pressure by pump 30 through line 31 into the cracking and soaking tube banks within chamber 13. For convenience of description, the entire tube bank 32 may 10 be regarded as comprising two sections 32a, 32b, the general direction of oil flow through which is in opposite directions. The relative widths of the sections are indicated by dotted line L—L'. The cracking tube bank includes all the tubes in 15 section 32b and the lower horizontal rows of tubes in section 32a below the dotted line L'. The soaking tubes then comprise the remainder of the tubes in section 32a above line L'. In practice, it may be desirable to substantially increase 20 the proportionate number of soaking tubes, assuming both the cracking and the soaking tubes as illustrated to be of the same length, although the drawings will serve to illustrate the general arrangement and principles involved.

The tubes in the horizontal rows of each section 25 are connected in series, as are also vertically adjacent rows, with some modification in the cracking tube bank as will later appear, so that, for example in tube bank section 32b, the oil entering the top row of tubes from line 31 flows down through the section in the path indicated by the arrows. The tubes in the lowermost rows of both sections are connected in series so that upon reaching the lower end of tube bank 35 32b, the oil then passes into the bottom tubes of section 32a and then flows upwardly through that section in the path indicated by the arrows. It will be noticed that tube bank section 32b is substantially narrower than section 32a, and that all 40 the tubes in the entire bank 32 have the same diameter. The relative number of tubes in the two sections 32a and 32b, may be varied in specific designs and in accordance with particular operating conditions which it is desired to maintain. Generally speaking, it has been found that best results in furthering the maximum production 45 of cracked distillate are obtained by heating the oil comparatively rapidly to the maximum cracking temperature, and then maintaining the oil at high temperature over an extended period of time, thereby enabling the cracking reaction to continue to the fullest extent under the existing temperature and pressure conditions.

In flowing downwardly through tube bank section 50 32b, the oil follows a path generally counter-current to the stream of hot combustion gases rising within chamber 13, and during this course of its flow, is heated comparatively rapidly to a cracking temperature in the neighborhood of 900° F., or above. Then after being heated to cracking temperature, the oil is held at high temperature over an extended period of time during the course of its upward flow through section 32a of the tube bank. While the oil preferably will be heated to cracking temperatures by the time it reaches the lower end of section 32b, it ordinarily will be heated to still higher temperatures in passing through the lowermost tubes of bank 55 32a. Due to the fact that the combustion gases will have become somewhat cooled before reaching the upper tubes in chamber 13, the oil temperature may drop somewhat as the oil flows upwardly through tube bank section 32a. However, the temperature drop will be comparatively 70 75

small, and the oil at the point of discharge into outlet line 34 will remain at a cracking temperature.

The particular features of the typical form of still described thus far are more specifically and extensively dealt with in my copending application Ser. No. 724,135, filed May 5, 1934, now U. S. Patent No. 2,034,094 on Oil cracking still. The present invention is more particularly concerned with the soaking tube bank and its structural 10 and functional association with the cracking tubes.

The soaking tubes receive the oil directly from the cracking tubes, and have a substantially greater oil passing capacity than the latter so 15 that the oil flows through the soaking tubes at substantially less velocity. In the broad aspects of the invention, the soaking tubes may be of any suitable size and arrangement capable of maintaining the oil stream in an elongated path of 20 flow and for an extended period of time at substantially reduced velocity. In the form of the invention shown in Fig. 1, I provide the same diameter tubes in both the cracking and soaking tube banks, but reduce the oil velocity within the 25 latter by passing the oil through two, instead of one series of tubes.

Thus as shown in Fig. 2, the oil leaving the final tube 35 of the cracking tube bank flows through fitting 36 into two tubes 37 and 38 in 30 the lowermost rows 39 and 40 of the soaking tube bank. The oil then passes through the soaking tubes at reduced velocity, alternate horizontal rows of the tubes being interconnected so that the oil takes the path indicated by the arrows. 35 The outlet tubes 41 and 42 of the two uppermost rows are connected by a fitting 43, similar to 36, with outlet line 34.

Outlet line 34 leads to a separator 45, which may consist simply of a hollow shell, and from 40 which the unvaporized residuum is continuously withdrawn through line 46. The vapors are discharged through line 47 and are subsequently condensed, fractionated or otherwise treated in suitable apparatus, not shown. Preferably a 45 high back pressure is maintained within both the cracking and soaking tubes, either by a valve located in the system at some point beyond the separator 45, as for example valve 48 in line 47, or by valve 49 in outlet line 34. In either case, a 50 substantial pressure preferably will be maintained in the separator 45, and where valve 49 is not provided, the pressures in the soaking tube outlet and the separator will be substantially the same. Ordinarily, however, valve 49 will be 55 installed in order that a considerably higher pressure than that necessary or desired in the separating chamber, may be maintained within the cracking and soaking tubes.

As shown in detail in Fig. 3, valve 49 is a gate-type comprising a body 49a and a gate in the form of a plate 50 having a central orifice 51 of such restricted area as to maintain the desired back pressure. During operation, the orifice plate is 60 in its lower closed position as illustrated, but 65 when it becomes necessary to blow out the tubes to remove accumulated carbon, plate 50 may be raised by turning screw 52 to permit unrestricted flow through the outlet line.

The variational form of the invention shown 70 in Fig. 4 is generally similar to that of Fig. 1, and corresponding parts are indicated by the same numbers with primes added. While in the variational form, similar conditions exist 75

throughout, the soaking tube section differs in that instead of having increased flow capacity and retarded oil velocity by virtue of two sets of tubes connected in parallel and individually 5 having the same cross sectional area as the cracking tubes, one set of soaking tubes of enlarged diameter is provided to produce the same retardation in the rate of oil flow. Thus as particularly illustrated in Fig. 5, the final cracking 10 tube 53 is connected by an enlarged return bend 54 with the initial soaking tube 55 of increased diameter. As before, the oil velocity through the soaking tube bank is at reduced velocity and under substantially the same pressure as that 15 existing in the cracking tubes. It will be understood that the relative numbers of cracking and soaking tubes may be varied to give best results, as may also the relative diameters of the tubes in the two sections.

20 In Fig. 6, I show a further variant provision whereby convection and reformation of the oil within the convection zone may occur at a pressure below the pressure in the cracking tubes. By placing a suitable valve 56, for example of the 25 type shown in Fig. 3, at the return bend 57 connecting the soaking and cracking tubes 55' and 53', any suitable pressure drop may be maintained on the oil at the point of entry to the soaking tube bank. Where valve 56 is used, valve 30 49' in the outlet line may be dispensed with and the back pressure in the soaking tubes controlled by valve 48' in the vapor outlet line.

Under typical operating conditions, fuel oil fed to preheating tubes 19 from line 21, will be 35 heated and discharged into separator 26 at a temperature around 500° F. and under any suitable pressure; for example, a pressure ranging from substantially atmospheric, up to 100 lbs. per sq. in. Then in flowing through the cracking and soaking tubes, the oil is heated to a 40 higher temperature which may range from 800° to 1000° F., and under a pressure within the range of from 300 to 850 lbs. per sq. in. In cases where valve 49 is used, the pressure in separator 45 45 may be reduced to in the neighborhood of from 200 to 300 lbs. per sq. in., under control of valve 48 in the vapor line.

I claim:

1. A tube still comprising opposed vertical walls 50 forming a heating chamber, a bank of horizontally extending tubes in said chamber, and means for feeding oil to said tube bank, the tubes in said bank being connected in series so that the oil flows downwardly through horizontal rows 55 of a relatively narrow vertically extending cracking section of the tubes, and subsequently passes upwardly through horizontal rows of a relatively wide adjacent vertically extending soaking section of the tubes located directly between the first mentioned section and one of said vertical walls, the cross sectional passage area of the tubes in said soaking section being substantially greater than the cross sectional passage area of the tubes in said cracking section, so that the oil flows through the soaking tubes at substantially reduced velocity.

2. A tube still comprising opposed vertical walls forming a heating chamber, a bank of horizontally extending tubes in said chamber, and means for feeding oil to said tube bank, the tubes in said bank being connected in series so that the oil flows downwardly through horizontal rows of a relatively narrow vertically extending cracking section of the tubes, and subsequently passes upwardly through horizontal rows 70

of a relatively wide adjacent vertically extending soaking section of the tubes located directly between the first mentioned section and one of said vertical walls, the cross sectional passage area of the tubes in said soaking section being substantially greater than the cross sectional passage area of the tubes in said cracking section, so that the oil flows through the soaking tubes at substantially reduced velocity, the aggregate length of the tubes in said soaking section being substantially greater than the aggregate length of the tubes in the cracking section. 5

3. A tube still comprising spaced vertical walls forming a preheating chamber and a heating chamber, oil heating tubes in said preheating chamber, a bank of horizontally extending tubes in said heating chamber, and means for passing oil from said preheating tubes to said tube bank, the tubes in said bank being connected in series 20 so that the oil flows downwardly through horizontal rows of a relatively narrow vertically extending cracking section of the tubes, and subsequently passes upwardly through horizontal rows of a relatively wide adjacent vertically extending soaking section of the tubes located directly between the first mentioned section and one of said vertical walls, the cross sectional passage area of the tubes in said soaking section 25 being substantially greater than the cross sectional passage area of the tubes in said cracking section, so that the oil flows through the soaking tubes at substantially reduced velocity. 30

4. A tube still comprising spaced vertical walls forming a preheating chamber and a heating chamber, oil heating tubes in said preheating chamber, a bank of horizontally extending tubes in said heating chamber, means for separating vapors from the oil leaving the preheating tubes and before entry of the oil to said tube bank, and means for passing oil from said preheating tubes to said tube bank, the tubes in said bank being connected in series so that the oil flows downwardly through horizontal rows of a relatively narrow vertically extending cracking section of the tubes, and subsequently passes upwardly through horizontal rows of a relatively wide adjacent vertically extending soaking section of the tubes located directly between the first mentioned section and one of said vertical walls, the cross sectional passage area of the tubes in said soaking section being substantially greater than the cross sectional passage area of the tubes in said cracking section, so that the oil flows through the soaking tubes at substantially reduced velocity. 45

5. A tube still comprising opposed vertical walls forming a heating chamber, a bank of horizontally extending tubes in said chamber, and means for feeding oil to said tube bank, the tubes in said bank being connected in series so that the oil flows downwardly through horizontal rows of a relatively narrow vertically extending cracking section of the tubes, and subsequently passes upwardly through horizontal rows 60 of a relatively wide adjacent vertically extending soaking section of the tubes located directly between the first mentioned section and one of said vertical walls, the cross sectional passage area of the tubes in said soaking section being substantially greater than the cross sectional passage area of the tubes in said cracking section, so that the oil flows through the soaking tubes 65 at substantially reduced velocity, and a burner positioned in the lower portion of said chamber 70

so that the combustion gases flow upwardly and counter-current to the oil flowing downwardly through said cracking section.

6. A tube still comprising opposed vertical walls forming a heating chamber, a bank of horizontally extending tubes in said chamber, and means for feeding oil to said tube bank, the tubes in said bank being connected in series so that the oil flows downwardly through horizontal rows of a relatively narrow vertically extending section of the tubes, and subsequently passes upwardly through horizontal rows of a relative-

ly wide adjacent vertically extending section of the tubes located directly between the first mentioned section and one of said vertical walls, the cross sectional passage area of the tubes in a plurality of upper tube rows in said relatively wide section being substantially greater than the cross sectional passage area of the remaining tubes in said tube bank, so that the oil flows through said enlarged cross sectional passage area tubes at substantially reduced velocity. 5 10

WILLIAM T. HANCOCK.
